(57) **CLAIM**

The ornamental design for an eye moisturizer having symmetric water containers, as shown and described.

DESCRIPTION

FIG. 1 is a perspective view of my new design showing an eye moisturizer having symmetric water containers;
FIG. 2 is a top plan view thereof;
FIG. 3 is a front elevation view thereof;
FIG. 4 is a rear elevation view thereof; and,
FIG. 5 is a side elevation view thereof, the opposite view being a mirror image.
